UNITED STATES PATENT OFFICE.

CHARLES J. SMITH, OF DEARBORN, MICHIGAN, ASSIGNOR TO FORD MOTOR COMPANY,
OF DETROIT, MICHIGAN.

AIRPLANE STABILIZER.

Application filed December 27, 1926. Serial No. 157,341.

The object of my invention is to provide an airplane stabilizer of simple, durable, and inexpensive construction. Still a further object of my invention is to provide in combination with the movable elevator planes of an airplane, an adjustable stabilizer plane whereby the stabilizer plane may be moved to position relative to a horizontal plane to compensate for varying load conditions.

Still a further object of my invention is to pivotally mount one end of the stabilizer plane on a fuselage and to adjustably mount the other end so that the angle of the stabilizer plane may be varied relative to the axis of the fuselage.

Still a further object of my invention is to provide a means for adjusting the angle of the stabilizing plane which may be extended to position adjacent to the pilot's seat, so that the position of the stabilizer plane may be adjusted either before or during flight.

With these and other objects in view my invention consists in the arrangement, combination and construction of the various parts of my improved device as described in the specifications, claimed in the claim, and disclosed in the accompanying drawings 30 in which:

Fig. 1 shows a somewhat diagrammatic elevation of an airplane fuselage having my improved stabilizing plane installed thereon.

Fig. 2 shows an enlarged elevation of the rear end of the fuselage shown in Fig. 1.

Fig. 3 shows a top or plan view of the device shown in Fig. 2.

Fig. 4 shows a vertical central transverse detailed view of the adjusting device for the stabilizing plane.

Fig. 5 shows an elevation of the device shown in Fig. 4, parts being broken away to better illustrate the construction, and

Fig. 6 shows a detail sectional view taken 45 on the line 6-6 of Fig. 4.

Referring to the accompanying drawings, I have used the reference numeral 10 to indicate generally a fuselage having a tail post 11 upon which a rudder 12 is pivotally mounted. The usual vertical stabilizing plane 13 and the tail skid 14 are also illustrated.

A horizontal stabilizing plane 15 of ordinary construction is provided adjacent to the rear end of the fuselage 10 and elevator

planes 16 are pivotally connected at 17 to the rear edge of the stabilizing plane 15.

The stabilizing plane 15 is pivotally mounted at 18 on the fuselage 10 to swing on a transverse horizontal axis so that the rear end of the stabilizing plane 15 may be 60 swung up and down. A housing 19 is secured to the tail post 11 in any suitable manner as by bolts 20. This housing is of substantially cylindrical shape and is provided with a cylindrical guard member 21 which is telescopically mounted therein for vertical reciprocation. Rotatably but non-slidably mounted in the housing 19 and 65 guard 21 is a threaded sleeve 22 which is provided with gear teeth at the lower end thereof. A worm 23 is rotatably but non-slidably mounted in a boss 24 on the housing 19 in position to co-act with teeth on the bottom of the sleeve 22 so that rotation of the worm 23 on a horizontal axis will impart 70 rotation on the vertical axis to a sleeve 22. A threaded shank 25 is mounted in the sleeve 22 to co-act with the threads in the latter so that rotation of the sleeve 22 will cause vertical reciprocation to the shank 25.

The upper end of the shank 25 is provided with a clevis 26 in which a link 27 is pivotally mounted. A similar clevis 28 is secured to the lower surface of the stabilizing plane 15 and is pivotally connected to the second end of the link 27.

From the construction of the parts just described it will be seen that rotation of the worm 24 will reciprocate the shank 25 to 90 raise or lower the rear end of the stabilizing plane 15 and to swing the latter on the pivot 18. An operating shaft 29 is fixed in the worm 23 as by splines 30 and extends forward along the fuselage to position adjacent to the pilot's seat 36 where it is provided with an operating handle 31. At intervals along the length of the operating shaft 29 brackets 32 are secured to the side of the fuselage to support universal bearing members 33 in which the shaft 29 is journalled so that warping or weaving of the fuselage will not interfere with the operation of the stabilizing plane adjusting means by the handle 31.

Among the many advantages arising from the use of my improved device, it should be specially mentioned that the adjustment of the stabilizing plane to meet load conditions reduces the wind resistance of the plane as 110

compared with the wind resistance which would be set up if the elevators alone were relied upon to compensate for different weights of load. Further the position of the stabilizer plane 15 may be adjusted before or during flight to correspond to the load carried so that the controls for the elevator 16 may always be normally in an intermediate position as distinguished from being 10 toward either limit of their possible movement. This of course makes the operation of the airplane by the pilot easier as his controls will always tend to remain in a normal position when in flight and the full 15 range of the movement of the elevators in either direction is assured for controlling the airplane.

A further advantage results from the fact that the control for the adjustment of the 20 stabilizing plane is extended to the pilot's compartment so that the position of the stabilizing plane may be varied during the flight. Some changes may be made in the

construction and arrangement of the various parts of my improved device without departing from the spirit of my invention and it is my intention to cover by my claim such changes as may be reasonably included within the scope thereof.

35

10

I claim as my invention:

In a device of the character described, a fuselage having a tail post at the rear end thereof, said fuselage having a horizontal longitudinal slot therethrough adjacent to said tail post, a stabilizer plane extended through said slot and pivotally mounted adjacent to its forward end within said slot, and means secured to said tail post and co-acting with said stabilizer plane to adjust that stabilizer plane about its pivot, the pivotal mounting and the adjusting device both being disposed substantially within the lines of the fuselage whereby the said parts may not increase the wind resistance of the stabilizer plane materially.

CHARLES J. SMITH.
